ALEXANDER PARKER, OF DANNEVIRKE, HAWKE'S BAY, NEW ZEALAND,
ASSIGNOR OF ONE-HALF TO FREEMAN LAWLOR JACKSON AND ED-
WARD ELEN PRIOR, OF DANNEVIRKE, HAWKE'S BAY, NEW ZEALAND

DRAFT, RAIN, AND DUST EXCLUDER FOR DOORS.

SPECIFICATION forming part of Letters Patent No. 761,704, dated June 7, 1904.

Application filed September 15, 1903. Serial No. 173,312. (No model.)

To all whom it may concern:

Be it known that I, ALEXANDER PARKER, a subject of the King of Great Britain, residing at Dannevirke, Hawke's Bay, in the Colony 5 of New Zealand, have invented a new and useful Improved Draft, Rain, and Dust Excluder for Doors; and I do hereby declare the following to be a full, clear, and exact description of the same.

10 This invention relates to improved means whereby the crack or opening at the bottom of a door, when the door is closed, may be covered, so as to prevent the entrance of dust, draft, or rain beneath the door. The means devised consists of a roller that is freely 15 mounted in a groove formed in the bottom edge of the door and which extends throughout the whole width thereof. This roller is supported by suitable bearings at each end of the 20 groove and is provided with a flat plate attached to its periphery at a tangent or radially throughout its whole length. The edge of this plate is preferably formed of rubber or other resilient material. When the roller is 25 partially revolved in its bearings, this plate will be turned down, so that its edge shall engage with the floor. To operate the roller to drop its plate, different devices may be employed.

30 In the drawings three distinct arrangements are shown; but I desire it to be understood that I do not confine myself exclusively to the use of all or any one of such, my invention consisting principally in the use of a roller and 35 tangential or radial plate.

Reference now being made to the accompanying drawings, Figure 1 is a front elevation of a door, the bottom portion being in section, so as to show the roller-plate mounted 40 therein. Fig. 2 is a cross-sectional elevation of the same looking from the right of Fig. 1 and illustrating one device by means of which the roller may be revolved.

a is the door, the bottom edge of which is 45 provided with a groove or tunnel *b*, running throughout its whole width. The ends of this groove are closed by the metal plates *c*, secured against the edges of the door, and these plates

form bearings to support the ends of the roller *d*. This roller also extends throughout 50 the whole width of the door and is supported in such a manner as to be free to revolve in its bearings. A plate *e* is secured, preferably, at a tangent to the periphery of the roller *d* along its whole length. This plate is adapted 55 to assume the position shown in Fig. 2 when the door is open, and when the roller is turned on the closing of the door (by means herein-after described) it will assume the position shown by dotted lines in Fig. 2, its extreme 60 edge thus forming contact with the floor beneath the door and closing up the crack or opening.

The outer end of the roller *d* has secured upon it a small pinion *f*. In the device shown 65 in Fig. 2 the teeth of this pinion as the door is closed are adapted to engage with the teeth of a metal block *g*, secured to the floor in the jamb edge of the doorway. By this engagement the pinion will be given a partial revolution, so as to turn the roller and cause the plate *e* to tip down and engage with the floor.

To raise the plate *e* from the floor as the door opens and to keep it normally raised, a helical spring *h* in slight tension has its bottom end secured to the periphery of the roller *d*, while its top end is secured to a recess 70 formed in the top of the groove *b*. As the roller is turned to drop the plate this spring will be drawn out into greater tension, so that 80 immediately the hold of the block *g* or bar *h* on the pinion *f* is released by partially opening the door this spring will revolve the roller back again, and thus draw up the plate *e* in to 85 its normal position clear of the floor.

What I claim as my invention, and desire to secure by Letters Patent, is—

In means for excluding draft, rain and dust from passing beneath doors, a groove or tunnel extending along the bottom edge of the 90 door, bearings secured to the door and closing the ends of the groove, a roller extending along the groove and carried in said bearings, a plate tangentially or radially secured to the roller throughout its length and teeth secured 95 upon the roller at one end, in combination

with a toothed plate secured upon the floor and having teeth thereon with which the pinion is adapted to gear when the door is closed so as to partially rotate the roller and a helical 5 spring secured at one of its ends to the roller and at the other end to the top of the groove or tunnel as specified.

In testimony whereof I have signed this specification in the presence of two subscribing witnesses.

ALEXANDER PARKER.
